(57) **CLAIM**

The ornamental design for a cooking appliance with burner grate, as shown and described.

DESCRIPTION

FIG. 1 is a front perspective view of a cooking appliance with burner grate according to the design;

FIG. 2 is a front perspective view of the cooking appliance with burner grate shown in FIG. 1 with unclaimed portions of the cooking appliance and additional burner grates that are unclaimed in FIG. 1 being removed;

FIG. 3 is a top plan view thereof;

FIG. 4 is a bottom plan view thereof;

FIG. 5 is a front elevation view thereof;

FIG. 6 is a back elevation view thereof;

FIG. 7 is a right side elevation view thereof; and,

FIG. 8 is a left side elevation view thereof.

The broken lines in the drawings depict portions of the cooking appliance with burner grate that form no part of the claimed design.

Dash-dot lines adjacent un-shaded areas represent bounds of the claimed design and form no part of the claimed design themselves.
